(**) Term: **14 Years**

Primary Examiner—Prabhakar Deshmukh
(74) *Attorney, Agent, or Firm*—Hollander Law Firm, P.L.C.

(21) Appl. No.: **29/094,432**

CLAIM

(22) Filed: **Oct. 1, 1998**

The ornamental design for a reclosable, expanded snack carton, as shown and described.

(51) **LOC (7) Cl. 09-07**

DESCRIPTION

(52) **U.S. Cl. D9/430; D9/305**

FIG. 1 is a perspective view of a reclosable, expanded snack carton with a bag liner taken from the top, rear and right side, showing my new design.

(58) **Field of Search** D9/430, 431, 424, D9/414, 305, 302; 206/524.3, 524.9; 220/495.01, 495.03, 495.05, 495.06; 229/114, 116.1, 106, 116, 117; D3/303

FIG. 2 is a rear elevational view thereof.

(56) **References Cited**

FIG. 3 is a left side elevational view thereof.

U.S. PATENT DOCUMENTS

FIG. 4 is a front elevational view thereof.
